UNITED STATES PATENT OFFICE.

JOHN C. NICHOLS, OF SHEBOYGAN, WISCONSIN.

BRIDGE FOR HARNESS PADS.

Application filed May 22, 1923. Serial No. 640,687.

To all whom it may concern:

Be it known that I, JOHN C. NICHOLS, a citizen of the United States, and resident of Sheboygan, in the county of Sheboygan, 5 and State of Wisconsin, have invented certain new and useful Improvements in Bridges for Harness Pads; and I do hereby declare that the following is a full, clear, and exact description thereof.

10 This invention relates to bridges for harness pads.

This case constitutes one of a series of cases filed simultaneously having elements 15 cooperating to form a harness without stitching.

Bridges, as heretofore constructed, for harness pads for use in guiding straps across the pad, such, for instance, as the back straps, have not proven wholly satisfactory for the reason that these bridges could not be so arranged that the straps guided thereby would at all times be retained within the bridge. It was frequently found that the bridges opened up slightly 25 from the pad and allowed the straps to work against the securing means producing either binding or rapid cutting of the securing means or the straps.

This invention is designed to overcome 30 the above noted defects and objects of such invention are, therefore, to provide a simple type of bridge piece adapted to be secured to a pad in a manner to prevent the gripping of the guiding strap beneath the ends of 35 the bridge piece, and to provide an extremely simple form of bridge piece which is serviceable and offers the minimum of resistance to the free passage of the guiding strap.

40 An embodiment of the invention is shown in the accompanying drawings, in which:

Figure 1 is an elevation of a portion of the pad showing the bridge piece in position thereon, parts of the securing means being 45 shown in section for clearness of illustration.

Figure 2 is a sectional view through the pad showing the bridge piece in position and partly in section, such view being on 50 a larger scale than Figure 1.

The bridge piece comprises an elongated transverse member 1 which is spaced from the pad and is slightly arched. It is preferably provided with rounded forward and rear faces as illustrated and has downwardly projecting end portions 2. These end

portions have integrally formed transversely slotted or eyeletted ears whose inner and bottom ends 3 (see Figure 1) merges into the end portions 2. The outer portions 4 of these ears are spaced from the inner portion and are positioned upwardly from the pad 5. It is to be noted that these ears extend upwardly and outwardly from the terminal portions of the bridge. 65

A convenient means of securing the bridge piece in position is by means of straps 6 which are passed through the ears and are folded over and stitched down to the pad as indicated at 7. This stitching 70 is preferably arranged closely adjacent the ears as shown in the drawings.

It is to be noted that by having the ears upwardly and outwardly directed that the securing means pulls downwardly upon the 75 outer portion 4 of such ears and forces the end portions 2 of the elongated arched member 1 and the inner portion 3 of the ears downwardly against the pad into binding engagement therewith. This construction precludes the sliding of the strap 8, such as the back strap, shown in Figure 1, from creeping or sliding beneath the end portion of the bridge piece and cutting 80 the securing means or the strap, and binding 85 of the strap.

It will, therefore, be seen that a highly desirable type of bridge piece has been provided which is of extremely simple construction, and that the bridge piece may 90 be secured to the pad in a simple manner with the assurance that its end portions will be at all times held in binding engagement with the pad.

Although a specific form of the invention 95 and one application thereof have been described in considerable detail, it is to be understood that the invention may be variously embodied and application thereof varied. It is, therefore, to be understood 100 that the invention is to be limited only as defined by the appended claims.

I claim:

1. The combination of a harness pad, a strap guiding bridge comprising a bridge 105 piece spaced from said pad and terminating in outwardly and upwardly directed ears, and securing means attached to said pad and engaging the outer portion of said ears to hold the lower portion of said ears 110 in binding contact with said pad.

2. A bridge piece for a harness pad com-

prising an elongated member having downwardly extending end portions, and apertured ears extending upwardly and outwardly from said ends.

5. 3. A bridge piece comprising an upwardly arched elongated member having downwardly extending ends, and apertured ears formed integrally with said ends and ar-

ranged transversely of said elongated member and projecting upwardly and outwardly from the ends of said elongated member.

In testimony that I claim the foregoing I have hereunto set my hand at Milwaukee, in the county of Milwaukee and State of Wisconsin.

JOHN C. NICHOLS.
